CARRYING CASE FOR A CLEANING APPLIANCE

Charles R. Margolies, Oreland, Pa., assignor to Glamorene Products Corporation, Clifton, N.J., a corporation of Delaware

Filed Jan. 12, 1968, Ser. No. 10,142

Term of patent 14 years

U.S. Cl. D87—1
Int. Cl. D3—99

FIG.1.

FIG.2.

FIG.3.

FIG.4.

FIG.5.

FIG.6.

FIG. 8.

I claim:

The ornamental design for a carrying case for a cleaning appliance, as shown and described.
